GARMENT HANGER

Clarke E. Warren, La Grange, Ill., assignor to
Mackie-Lovejoy Manufacturing Company, Chi-
cago, Ill., a corporation of Illinois

Application August 27, 1948, Serial No. 46,469

3 Claims. (Cl. 223—96)

1

This invention relates to an improved garment hanger of the type shown in Deknatel Patent No. 1,955,792.

In a device of this type jaws are provided to engage the garment to be supported and the jaws in turn are supported by arms which are provided with intermediate portions or cranks. A lever is pivotally mounted on one of the cranks and engages the other crank and serves to draw the two jaws together against the considerable force exerted by the resistance of the arm and crank elements to the deformation occasioned by the operation of said lever.

That patent indicates that the wearing away of the parts can be avoided by the provision of a bearing in the form of a roller which is rotatably mounted on that crank over which the lever slides.

Heretofore, the roller bearing has been fabricated from a short strip of steel which is curled up into more or less of a cylindrical shape. I have found that when the spring which urges the jaws apart is secured at its free ends to the cranks, as shown in the aforementioned patent, that there is a tendency on the part of the ends of the spring to push the roller laterally so that it rides up on one of the crank arms and is deformed. When this occurs, the roller will be wedged in such a position that it will not rotate and hence the advantages of using the

roller are lost. Furthermore, in the arrangement shown in that patent, it is desirable that the axis of the helix of the spring coincide with the axis of rotation of the arm and crank elements about each other. However, since the parts are formed by bending operations, it is difficult to maintain close tolerances, with the result that this optimum condition seldom obtains. If the spring arms are shorter than the crank arm, the spring is likely to break. If the spring arms are too long, they will buckle, causing permanent deformation of the spring. In either event, the ends of the spring tend to slide off the crank and to creep up the crank arms with the result that the spring arms are subjected to a torsional deformation which frequently results in breakage of the spring.

It is believed that the above-mentioned difficulties encountered with the prior art spring construction are also due in part to the fact that the ends of the spring are anchored to the transversely disposed crank elements. Due to the manufacturing difficulties, these are not necessarily spaced equidistantly from the axis of rota-

tion nor can the ends of the spring be wrapped around the cranks in such a manner that the effective radius of each spring arm corresponds to that of its associated crank. Thus, stresses are set up in the spring which tend to cause the spring ends to slide off the crank, but which would be avoided if the spring ends were slidably secured to two radially disposed elements.

It is an object of my invention to provide an improved garment hanger in which the aforementioned wedging of the cylinder bearing will not take place, and in which an improved spring is provided which is not subject to the aforementioned objections.

It is a further object of this invention to provide in a garment hanger of this type, a roller bearing which is made from brass or other material having a low frictional coefficient with respect to the nickel plated steel of which the lever is fabricated. Thus the lever operates much more readily even though the rotation of the roller bearing is impeded due to its variation from true cylindrical. Actually, I have found that it is difficult to fabricate a small sheet of metal into a true cylinder since the end portions cannot be bent as readily as the intermediate portion of the strip. Thus the resulting cylinder has two adjacent flat spots which are disposed at an angle with each other, each of these flat spots representing the end portions of the original strip or blank. At those times when the lever is being drawn up to urge the jaws together, there is considerable pressure exerted by the lever on the roller bearing and if the latter is in such an angular position that one of the flat spots is engaged by the lever, then the roller will not rotate. By fabricating the cylinder bearing from brass stock as pointed out above, the friction between the parts at these times is avoided.

With reference now to the drawings in which like reference numerals designate like parts:

Fig. 1 is a perspective view of the preferred embodiment of my invention with the jaws in open position;

Fig. 2 is a section on a vertical plane near the center of the hanger with the jaws in closed position;

Figs. 3 and 4 are detailed views of the spring, and

Fig. 5 is an enlarged detailed view showing the roller bearing and its relationship with the adjacent parts.

The garment hanger comprises a pair of jaws 55 10 and 11 which are preferably made of strips

of wood which are lined with felt pads 12. The jaws are formed with openings which are adapted to receive the end portions of two rods which support the jaws. The rod supporting jaw 10 is provided with jaw arm portions 13 at either end which are separated by an intermediate portion comprising a crank 14 and crank arms 15. The rod supporting jaw 11 comprises jaw arm portions 16 which are separated by an intermediate portion comprising a crank 17 and crank arms 18. The two portions between the crank arms 18 and the jaw arms 16 are formed into aligned helices 19 which embrace correspondingly disposed pintle portions 29 on the opposite rod. Thus, the jaws 10 and 11 are pivotally mounted with respect to each other.

The clamping lever 20 has a bent end 21 which pivotally engages crank 17. The clamping lever also has a camming portion 22 which is adapted to ride over crank 14 and bring the jaws into clamping engagement, this position of the parts being shown in Fig. 2, although the clamping lever is omitted for purposes of clarity. The crank 14 is provided with roller bearing 23 which is preferably made of a strip of brass stock which is bent into more or less cylindrical shape as shown in Fig. 5. As indicated above, it is difficult to provide a roller bearing of true cylindrical shape since it is bent around the crank after the crank has been formed. Thus, it is generally provided with flat spots 23a and 23b.

The jaws are urged into their open position by means of a spring 24. One end 25 of the spring is bent around one of the jaw arm positions 13 and the other end 26 is bent around the jaw arm portion 16. The middle portion of the spring is formed into a loop 27 which passes over and around the two rods at one of the helices 19 or at a point adjacent thereto and is provided with a comparatively narrow neck as indicated by the reference numeral 28. At least one of the end portions 25 and 26 preferably engage the jaw arm portions loosely to permit a certain amount of sliding movement during operation.

In operation, the spring 24 tends to hold the jaws apart when the clamping lever 20 is in the position shown in Fig. 1. Since the loop 27 of the spring passes over the helix 19, the spring cannot drop down to a position in which the spring limits the extent of jaw opening, and in which position the spring is subject to breakage if the jaws are forced apart. The narrow neck 28 prevents the spring from riding up the jaw arms more than a limited amount.

Since the ends of the spring are not secured to the two cranks there will be no tendency to cause the roller bearing to become wedged against one of the crank arms. Even though in some instances the roller bearing may not rotate due to its departure from true cylindricality the fact that it is made of brass serves to reduce the friction otherwise present in the operation of the device.

As shown in the drawings, the outer end of the clamping lever may be formed into a hook so that the garment hanger may be conveniently supported from a clothes rod. However, other supporting means may be provided and the clamping lever may be utilized solely for clamping purposes.

I claim:

1. A garment hanger comprising two jaws, a

rod for supporting each of said jaws for pivoted movement with respect to each other, each of said rods comprising two end portions bent to form jaw arms and an intermediate portion including a crank, one of said rods being bent around the other at points between said crank and said jaw arms to form two aligned hinge portions, a clamping lever pivotally mounted on one of said cranks and adapted to engage the other of said cranks to bring said jaws into clamping engagement with each other, and a spring having a single looped portion passing around said rods at one of said hinge portions and having its ends slidably secured to said jaw arms for urging said jaws out of clamping engagement, said single looped portion comprising a loop of less than 360° and having a constricted neck portion which is narrower than the diameter of said hinge portions to limit the sliding movement of said ends with respect to said jaw arms.

2. A garment hanger comprising two jaws, a rod for supporting each of said jaws for pivoted movement with respect to each other, each of said rods comprising two end portions bent to form jaw arms and an intermediate portion including a crank, one of said rods having axially aligned helical portions at points between said crank and said jaw arms and the other of said rods having axially aligned pintle portions at points between said crank and said jaw arms, said helical portions surrounding said pintle portions to provide a hinged connection between said rods, a clamping lever pivotally mounted on one of said cranks and adapted to engage the other of said cranks to bring said jaws into clamping engagement with each other, and a spring having two ends and an intermediate looped portion passing around both of said rods at a point in the vicinity of said hinged connection, each end being wrapped around one of said jaw arms for urging said jaws out of clamping engagement, at least one of said ends being slidably associated with its corresponding jaw arm, said looped portion comprising a single loop of less than 360° whereby said spring may be removed from said hanger.

3. In a garment hanger of the type described having two jaws and a rod for supporting each of said jaws for pivoted movement with respect to each other, each of said rods comprising two end portions bent to form substantially radially disposed jaw arms and an intermediate portion including a crank, one of said rods being bent around the other at points between said crank and said jaw arms to form two aligned hinges and, a spring having a looped portion passing around one of said hinges and having its ends slidably secured to said jaw arms, said looped portion comprising a single loop of less than 360°.
